UNITED STATES PATENT OFFICE.

ISAAC W. HOOVER, OF MILAN, OHIO.

POTATO-DIGGER.

SPECIFICATION forming part of Letters Patent No. 318,254, dated May 19, 1885.

Application filed March 16, 1885. (No model.)

To all whom it may concern:

Be it known that I, ISAAC W. HOOVER, of Milan, Erie county, and State of Ohio, have invented certain new and useful Improvements 5 in Potato-Diggers, the nature of which consists in a novel construction and arrangement of mechanism for digging or removing the tubers from the ground, sifting and separating them from the earth, stones, weeds, and stalks, 10 and delivering them at the rear of the machine, on one side, into a receptacle or upon the ground to be gathered up, and the weeds or refuse not already sifted from the potatoes are discharged from the machine on the opposite side from the delivery of the potatoes.

The mechanism consists, in part, of an endless open elevator and a screen or sifter, on which the potatoes are moved from the ground by a shovel or scoop at the front end of the 20 machine. This elevator and screen aid in sifting the dirt and refuse from the potatoes, which are carried by the elevator to a separator and sifters, where again the separation of the potato from the refuse is induced, and the 25 potatoes delivered from the machine on one side and the refuse upon the other.

That the said machine may be more fully understood, reference will be had to the following specification, and to the annexed drawings, making part of the same, in which—

Figure 1 is a side elevation; Fig. 2, a plan view. Figs. 3 and 4 are detached sections.

In the drawings like letters denote like parts in the several views, in which A represents 35 the frame of the machine, made of iron, wood, or of both, combined in such manner as may be best adapted to the purpose designed. Said frame is mounted upon the driving-wheels B B, to which is attached the gear C, 40 engaging the pinion D, Figs. 1, 2. The shaft of the pinion D is provided with bearings in the sides of the frame A, and on the shaft is a drum or roller, E, Fig. 2. At each end of this roller is a sprocket-wheel having a sprocket. 45 belt or chain, F, on each end of the drum. These chains or sprocket-belts extend to and engage each, respectively, a sprocket-wheel on the ends of the roller G, Fig. 2.

H H are also sprocket belts or chains, each 50 connected, respectively, to a sprocket-wheel on the said roller G, and pass over or around

the ends of the roller I, placed in the lower end of the machine. Over the rollers G and I pass a series of belts, J, having a number of cross-slats, K, attached thereto. Between the belts 55 J is arranged a series of rods, L, forming an inclined sieve or screen. At the lower front end is a scoop-shovel, M, attached to the frame, as seen in the drawings. On each side of this shovel is a rotary cutter, N, each having a 60 caster-wheel-like joint-connection at O, with its respective arm P extending back and fastened to the sides of the frame, as seen in Fig. 1 more plainly.

Q is a draft-bar, to which the team is attached for drawing the machine. The caster-joint O connection of the rotary cutters N to the arms P P allows each one to turn as the nature of the work in the operation of the machine may require, in turning to avoid ob- 70 structions, or for other cause.

Attached to the side of the machine is a shifter, R, Fig. 2, having a lever, one end of which engages the hub of the pinion D, which is fitted to the shaft with a feather-key, so that the pinion may be moved in and out of gear with the spur-wheel C. By means of this gear lever shifter, which is pivotal in its attachment to the machine, the working mechanism may be moved in and out of gear, so that the 80 machine can traverse from one place to another with only the driving or carrying wheels B B in operation until put in gear with the pinion D.

The handles S S form a frame which is piv- 85 oted or journaled at its inner ends upon a sleeve, T, projecting from the side of the frame A, as indicated in Fig. 3, which is a transverse vertical section in the line x x, Fig. 2. This attachment of the handles S S is alike on both 90 sides of the machine—that is, the arrangement described in Fig. 3 is the same on both sides at U U'; hence the description of Fig. 3 will be sufficient for both. Said Fig. 3 is an enlarged view.

The journals V of the roller G extend through the sleeves, (one is shown at T,) and to the ends of the respective journals is keyed a pulley, W W, from which a belt passes and engages a pulley, X, respectively, on each 100 side, as seen in Fig. 2. These pulleys X X are attached to the crank-shaft a, Fig. 2, jour-

naled in standards *b b* on the frame-handles. To the cranks of the shaft *a* are hung raking-arms *c c*, the upper ends of which are connected to a rod or link, *d d*, which is attached 5 to a cross-bar, *e*, Figs. 1 and 2. By this arrangement of the raking-arms and their attachment by links to the cross-bar they have a stirring and drawing or raking backward movement and a lifting or raising motion as 10 they are moved forward by the action of the cranks as the shaft revolves, which is seen in the drawings, and fully set forth. To this frame-handle or handle-frame is journaled a shaft, *f*, having crank ends *g g*, which are connected to one end of the links *h h*, while the opposite ends of said links are fastened to the frame of the machine at any suitable point. 15 This link *h* arrangement is alike on both sides of the machine, as seen in the drawings.

20 A lever, *i*, is secured to the shaft *f*, by means of which lever in its relation and cooperation with the shaft *f* and links *h h* the said handle-frame with its attachments arranged as herein shown may be raised and lowered to or from the ground, as the nature 25 of the case may require, according to the condition of the ground, and held in such position by the lever being engaged in the ratchet or rack *j*, Figs. 1 and 2. Connected with the 30 sifting-frame *S* are arranged a series of curved rods or bars, forming a vibrating sifter or separating - screen, *k*, the discharging ends of which are free, while the opposite ends are fastened to the cross-bar *l*, forming a part of 35 the sifting-frame.

Directly under the bars or rods *k* is another 40 sifting-screen, *m*, the bars of which are also curved laterally, but in an opposite direction to the screen above it. The bars of the screen *m* are closer together than bars *k* in the screen above, to make the lower screen finer in sifting. The free ends of the screen-bars *m* extend out in the rear nearly to the ends of the handles, while the opposite ends are fastened 45 to the same cross-bar, *b*, as the sifter *k* above. These sifters vibrate jointly by means of a connecting-rod, *n*, on each side of the frame *S*. One end of each rod is jointed to a wrist-pin in the pulleys *W W*, and the other ends to 50 the vibrating sifter-frame at *n'*. (Indicated in Figs. 1 and 2.) The sifter-frame is hung by vibrating links *O' O'*—two on each side—to the frame *S* in Fig. 1. These links or hangers have a jointed connection at their terminals, 55 to allow of the sifter's vibration longitudinally by the action of the pulleys *W W* in transmitting motion to the sifters through the links *n n*, journaled to a wrist on the pulleys, motion being conveyed to the pulleys 60 from the driving-wheels by the gearing *C D*, thence to the roller *G* by means of the sprocket wheels and belts *F*, the pulleys *W W* being upon the shaft ends of the roller *G*, and by means of the links *n n* the sifters are vibrated, 65 as before stated.

In the practical operation of the said machine the team is attached to the draw-bar *Q*,

and the driver manages the machine by the handles of the frame *S* in the rear similar to the management of a plow. As the machine 70 moves along, the rotary cutters separate or divide the hills of potatoes from the valleys between longitudinally. This separation allows the shovel to scoop up the hills of potatoes, which pass back over the roller *I* onto the open series of endless belts *J*, which form an elevator and an inclined sifter, which carries the potatoes, stalks, weeds, and dirt that is not sifted through the elevator and between the bars *L*, up over the roller *G*, onto the sifter 75 *k*, and by means of the raking-arms *c c* the mass carried up is so agitated and separated that the potatoes will pass through the upper vibrating sifter, *k*, to the lower vibrating sifter, *m*, while the weeds and stalks are passed off 80 by the motion of the sifter and deposited on one side of the machine, and the potatoes are again sifted by the lower screen or sifter, *m*, and deposited on the opposite side of the machine on the ground to be gathered up or in 85 a receptacle for them. In Fig. 2 the curved form of the vibrating sifters *k m* is seen, showing the bars of the sifters curved in an opposite direction to each other, for the purpose of the terminal separation of the refuse 90 from the potatoes and discharging the same 95 separately on opposite sides of the machine.

As the load of potatoes, dirt, stones, stalks, &c., is being carried up over the roller *G*, Fig. 2, onto the sifters *k m*, a large amount of 100 dirt, refuse, &c., is sifted through the series of endless belts *J* and bars *L* of the screen to the ground, and the larger or more bulky parts are carried up by the endless belts *J* onto the vibrating sifters *k m*, and again a sifting and separation of the load takes place by 105 depositing the refuse on one side of the machine and the potatoes on the other, as before stated.

By means of the sprocket wheels and belts 110 connecting the rollers *G* and *I*, and also the rollers *E* and *G*, a positive motion is given to the operating mechanism, rotating the endless belts, raking-arms, and sifters from the gear *C*, Fig. 2, attached to the driving-wheel and 115 transmitted to the pinion *D*, thereby causing a certainty of operation.

What I claim as my improvements, and desire to secure by Letters Patent, is—

1. In a potato-digger, the vibrating double 120 sifters *k m*, arranged one above the other, having curved bars in reverse direction to each other, in combination with raking-arms *c c*, journaled upon a crank-shaft, substantially as and for the purpose herein set forth.

2. In a potato-digger, the adjustable double 125 sifters *k m*, arranged one above the other and hung by links in connection with the frame *S*, to admit of longitudinal vibration thereof, as shown, in combination with the raking-arms *c c*, and crank-shaft arranged above the sifters, as and for the purpose substantially as specified.

3. In combination with a potato-digger, the

sleeve T, projecting from the side of the frame A, with the shaft of the roller G, having its bearing therein, and the inner ends of the frame S, hung upon the outside of said sleeve, 5 and arranged in co-relation with the adjustable vibrating sifters k m, substantially as and for the purpose herein set forth.

4. In a potato-digger, the adjustable frame S, journaled or hung at its inner end upon the 10 sleeve T, in combination with the vibrating sifters k m, links h, a shaft having cranks g g,

and lever i, with a ratchet for engaging said lever, whereby the said frame may be raised or lowered and held in position in the manner and for the purpose substantially as hereinbefore described. 15

In testimony whereof I affix my signature in presence of two witnesses.

ISAAC W. HOOVER.
